UNITED STATES PATENT OFFICE

HERBERT A. FRAZIER, OF BUTLER, PENNSYLVANIA

DEVICE FOR APPLYING ANTISKID CHAINS

Application filed May 8, 1930. Serial No. 450,837.

The application of anti-skid chains to the wheels of motor vehicles is usually attended with considerable difficulty especially when the application is made on the road. One of the chief difficulties is in connecting the ends of the side chains with sufficient tautness.

The object which I have in view is the provision of a device which is adapted for advantageous use in applying anti-skid chains and which will enable such chains to be properly and conveniently applied without requiring the jacking up of the wheels.

For this purpose I have invented a device which comprises a length of flexible material, such for instance as a stout strap of webbing, one of whose ends is provided with a chain engaging hook and whose other end is provided with a tension spring and hook, and whose intermediate portion is provided with a slidable buckle to which is connected a short flexible member or strap which has its free end provided with a hook.

My device may also be used as a spreader to maintain the anti-skid chain snugly in place on the vehicle.

In the accompanying drawings, wherein I have illustrated a practical embodiment of the principles of my invention, Fig. 1 is a side elevation of a vehicle wheel showing two of my devices employed in applying the anti-skid chain to the wheel.

Fig. 2 is a similar view showing one of my devices employed in a different manner for the same purpose.

Fig. 3 is a similar view showing another manner of employing my device for the same purpose.

Figs. 4 and 5 are similar views showing my devices employed as spreaders.

Fig. 6 is an enlarged view of the device shown separately.

Referring to the drawings, my device comprises a length or strap 1 of flexible material, preferably stout webbing, and of suitable length. To one end of the strap 1 is permanently attached the chain hook 2 while the other end of said strap has permanently attached thereto one end of the stout helical spring 3 whose outer end has attached there-

to the chain hook 4. The hook 4 is preferably swivelled to the spring 3. 5 represents a buckle which is slidable on the strap 1 and also flexible at any point thereon. This buckle may be of any suitable character but I prefer to use and have shown the usual tongueless buckle in common use in connection with webbing straps for trunks and the like. Connected to the cross bar of said buckle is a relatively stout strap 6 of the same material as the strap 1 and the free end of the strap 6 is provided with a permanently attached hook 7.

In Fig. 1 I show one manner in which my device may be used to apply an anti-skid chain to a vehicle wheel. Here I show two of the devices in use. The anti-skid chain is laid or draped over the wheel with the ends of its side chains 8 at either side at the bottom of the wheel and drawn together. The hooks 2 and 7 are now hooked into links of the inner and outer side chains with the fork of the device straddling the felloe of the wheel. One of my devices is thus installed at either side as illustrated in Fig. 1. The devices are then tightened by sliding the buckle 5 toward the hook 2 until the ends of side chains are snugly anchored in place. When the devices have thus been applied and tightened at either side, the long ends of the devices may be hooked up out of the way as by engaging the hooks 4 in the links of the side chains at the proper elevation at either side.

The vehicle is then moved to revolve the wheel and bring the ends of the side chains into a convenient position where they may be readily connected by the usual connectors.

In Fig. 2 I show the hooks 2 and 7 of the device engaged with the opposite ends of a side chain and the device then tightened by sliding the buckle along the strap 1 toward the hook 2. After the ends of the chains are brought together they are connected in the usual manner.

In Fig. 3 I show two of my devices thus applied to the outer and inner side chains and the long ends of the devices hooked up out of the way. The wheel is then revolved

to bring the ends up from the bottom to a convenient position and they are then connected together in the usual manner.

In Figs. 4 and 5 I show two uses of a pair **5** of my devices as spreaders employed to keep the anti-skid chain taut on the wheel.

My device is inexpensive and durable and convenient to carry in the tool box or compartment of a motor vehicle. Its use **10** renders the application of anti-skid chains to vehicle wheels convenient and expeditious, and may be used with advantage as a spreader to keep the anti-skid chains tautly in position on the wheels.

15 What I claim is:—

1. A device for applying anti-skid chains to vehicle wheels which comprises in combination a length of flexible material, a hook attached to one end of the same, a helical **20** spring attached to the other end of the same, a hook attached to the other end of said spring, a second length of flexible material, a tongueless buckle mounted on the first named length and provided with a cross bar **25** to which one end of said second length is attached, and a hook on the other end of said second length.

2. A device for applying anti-skid chains to vehicle wheels which comprises in combination **30** a flexible strap, a hook attached to one end of the strap, a helical spring attached to the other end of the strap, a hook attached to the free end of the spring, a tongueless buckle mounted on said strap, a **35** second strap attached to the bar of said buckle, and a hook on the free end of the second strap.

3. A device for applying anti-skid chains to vehicle wheels which comprises in combination **40** a strap formed of a length of webbing, a hook attached to one end of said strap, a helical spring attached to the other end of the strap, a hook attached to the free end of the spring, a tongueless buckle **45** mounted on said strap, a second strap having its one end attached to the cross bar of said buckle, and a hook on the free end of said second strap.

Signed at Butler, Pa., this 17th day of **50** March, 1930.

HERBERT A. FRAZIER.
